LAMP POST

Bertil L. Habro, Lidingo, Sweden, assignor to AB
Linjebyggnad, Stockholm, a corporation of Sweden

Filed Sept. 5, 1967, Ser. No. 8,487

Term of patent 14 years

Int. Cl. D26—03

U.S. Cl. D48—31

FIG. 1

FIG. 3

FIG. 2

FIG. 1 is a perspective side view of the lamp post;
FIG. 2 is a fragmentary perspective view of the post
as seen obliquely from below;

FIG. 3 is a fragmentary perspective view of the post
as seen obliquely from above.

Specifically, the lamp post is overall purely conical in shape in that the extending ribs taper from a maximum at the base toward a minimum diameter at the outer diameter of the inner hollow supporting member as is clearly shown in FIGS. 1 and 3.

I claim:

The ornamental design for a lamp post, as shown and described.
